CONCRETE FORM TIE WIRE TIGHTENER AND FASTENER

Filed April 20, 1938

INVENTOR,
ALEXANDER T. PRYNE.
BY *Martin O. Smith, Atty*

UNITED STATES PATENT OFFICE

2,152,090

CONCRETE FORM TIE WIRE TIGHTENER
AND FASTENER

Alexander T. Pryne, Los Angeles, Calif.

Application April 20, 1938, Serial No. 203,217

8 Claims. (Cl. 24—19)

My invention relates generally to concrete forms and more particularly to a device for tightening and securing the tie wires that pass through the walls of the form.

The principal objects of my invention, are to generally improve upon and simplify the construction of the existing forms of concrete form tie wire tightening and anchoring devices; further, to provide a device of the character referred to that is simple in construction, strong and durable, composed of a minimum number of parts, and which may be conveniently applied to the wall of a concrete form and readily manipulated to tighten the tie wires and twist the ends together, so as to hold the walls of the form firmly in proper spaced relation and further, to provide simple means for mounting the main body portion of the device on the form so that said body portion may be easily and conveniently rotated to draw the tie wires taut and retain the same in such condition.

With the foregoing and other objects in view, my invention consists in certain novel features of construction and arrangement of parts that will be hereinafter more fully described and claimed and illustrated in the accompanying drawing in which:

Fig. 1 is a front elevational view of a tie wire tightening and securing device constructed in accordance with my invention.

Fig. 2 is a side elevational view of the device in position upon the wall of a concrete form.

Fig. 3 is a horizontal section taken on the line 3—3 of Fig. 1.

Fig. 4 is a plan view of the base member of the device before the arms thereof are bent around the edge of the rotating member of the device.

Fig. 5 is a horizontal section showing the wire receiving member mounted for rotation upon a nail that is driven into the form.

Fig. 6 is an elevational view of a combined wrench and nail-set that is utilized in connection with my improved device.

Fig. 7 is a plan view of the end of the tool and showing the nail-set.

Referring by numerals to the accompanying drawing, 10 designates a disc that is preferably formed from sheet metal of proper thickness and formed integral with the edge of said disc is a plurality of outwardly projecting arms 11, there preferably being four of these arms and the same disposed ninety degrees apart.

Struck from the material forming the disc, 10 are two or more prongs 12 which are bent at

right angles to the plane occupied by the disc and said prongs being driven into the wall of the form to which the device is applied, thereby firmly anchoring the base member 10.

Mounted to rotate on the face of the disc 10, 5 is a disc 13 preferably of cast metal and which constitutes the base of the rotary wire receiving member of the device and to retain this member for rotation on the disc 10, the outer portions of the arms 11 are bent around the edges 10 of disc 13 to form retaining hooks 14.

Disc 13 is slightly larger in diameter than disc 10 and formed in that portion of the disc 13 that projects beyond the edge of disc 10, is a series of notches 15, any one or more of which 15 may receive a nail that is driven into the wall to which the device is applied for the purpose of holding the rotary member of the device against reverse rotation after it has been rotated to draw the tie wires taut and to anchor 20 the ends of said tie wires. The head of a nail that is driven through one of the notches 15 into the wall of the form to hold the disc 13 against rotation is illustrated in Fig. 1.

Formed integral with and projecting outwardly from the central portion of the rotary disc 13, is a stud 16 preferably of hexagonal contour in order to receive a wrench or like tool utilized in rotating the disc 13 and stud 16 and formed in this stud is an axial bore or chamber 17, the 30 lower end of which communicates with an aperture 18 that is formed through the center of disc 13.

The wall of stud 16 that surrounds the bore 17 is provided with oppositely arranged longitudinally disposed slots 19 that gradually taper toward their inner ends. This tapering of the slots 19 enables the latter to receive wires of different diameters and when the wires are pressed into said slots toward the lower ends 40 of the latter, the wires have direct contact with both edges of both slots.

In Figs. 6 and 7 I have illustrated a tool particularly designed for use in connection with my improved tie wire tightening and anchoring device, said tool being preferably cast in a single piece and comprising an arm 20 that functions as a handle and one end of said arm being enlarged as designated by 21.

Formed in the enlarged end 21 of the tool, is 50 a pair of parallel slots 23 that are adapted to receive those portions of the stud 16 to the sides of the slots 19 and the bar 24 of metal that is disposed between the slots 23 enters the slots 19 when the tool is applied to the stud 16 for 55

the purpose of rotating the same on the base 10. In Fig. 6 the stud 16 is shown by dotted lines.

Projecting laterally from the end of the arm 20 opposite head 21, is a short cylindrical stud 24 that functions as a nail-set and which is used when a nail is driven through aperture 18 into the wall of the form so as to provide an axis upon which disc 13 and stud 16 may rotate.

In Figs. 1, 2 and 3 the rotary member of the 10 device comprising the disc 13 and stud 16 is shown mounted for rotation upon the base 10 and in Fig. 5 the rotary member comprising base 10 and stud 16 is shown mounted for rotation on a nail that is driven into the wall of the form.

15 In the use of my improved tie wire tightening and anchoring device, those portions of the tie wire that extend beyond the wall of the form to which the device is applied are brought to the stud 16 and said wires are pressed into the lower 20 ends of the slots 19. The end portions of the wires that project beyond the slots 19 are then bent anti-clockwise partially around the exterior of stud 16, after which the slotted head of the tool is applied to the outer portion of stud 25 16 and said tool is moved clockwise, thus imparting rotary motion to disc 13 and stud 16.

Such action winds portions of the tie wire on to the stud 16 and when the wire has been drawn to the desired degree of tautness a nail is driven 30 through one of the notches 15 into the form on which the device is positioned, thus holding the rotary member of the device against reverse rotation and consequently anchoring the end portions of the tie wire securely to said device.

35 Where the rotary member of the device comprising disc 13 and stud 16 are used without the base comprising disc 10 and arms 11, said rotary member is mounted for rotation on a nail that is driven through aperture 18 into the wall of the 40 form and the driving of such nail is effected through the use of the nail-set 24 which readily enters bore 17 in the rotary member.

Thus it will be seen that I have provided a 45 concrete form tie wire tightening and anchoring device that is relatively simple in construction, inexpensive of manufacture and very effective in performing the functions for which it is intended.

It will be understood that minor changes in 50 the size, form and construction of the various parts of my improved concrete form tie wire tightener and fastener, may be made and substituted for those herein shown and described, without departing from the spirit of my invention, the scope of which is set forth in the appended claims.

I claim as my invention:

1. A concrete form tie wire tightening and anchoring device comprising a base, a stud pro-

jecting from the center of said base, said stud provided with an axial bore, the lower end of which passes through the center of the base and the wall of said stud surrounding the bore being provided with longitudinally disposed slots. 5

2. A concrete form tie wire tightening and anchoring device comprising a base, a stud projecting from the center of said base, said stud provided with an axial bore, the lower end of which passes through the center of the base and 10 the wall of said stud surrounding the bore being provided with longitudinally disposed slots that taper toward their inner ends.

3. A concrete form tie wire tightening and anchoring device comprising a base, a stud projecting from the center of said base, said stud provided with an axial bore, the lower end of which passes through the center of the base, the wall of said stud surrounding the bore being provided with longitudinally disposed slots and 20 said base being provided with a notch for the reception of anchoring means that is seated in the form to which the device is applied. 15

4. In a device of the class described, a body provided with a slot for the reception of a tie 25 wire, there being an aperture formed in said body and extending from the bottom of said slot to one end of said body and means for maintaining the device in fixed position.

5. In a device of the class described, a base, 30 prongs projecting from said base, hooks on the edge of said base, a member mounted for rotation on said base and retained thereon by said hooks and said member being provided with a tie wire receiving slot. 35

6. In a device of the class described, a base, prongs projecting from said base, hooks on the edge of said base, a member mounted for rotation on said base and retained thereon by said hooks and said member being provided with a tie 40 wire receiving slot, which slot gradually decreases in width toward its inner end. 40

7. In a device of the class described, a base, prongs projecting from said base, hooks on the edge of said base, a member mounted for rotation on said base and retained thereon by said hooks, said member being provided with a tie 45 wire receiving slot and means for holding the slotted member against rotation on said base.

8. In a device of the class described, a base, prongs projecting from said base, hooks on the edge of said base, a member mounted for rotation on said base and retained thereon by said hooks, said member being provided with a tie 50 wire receiving slot, which slot gradually decreases in width toward its inner end and means for holding said slotted member against rotation on said base. 55

ALEXANDER T. PRYNE.
